(57) **CLAIM**

We claim the ornamental design for a sash lock housing, as shown and described.

DESCRIPTION

FIG. 1 is a perspective view of the sash lock housing of the present invention;

FIG. 2 is a side view of the sash lock housing shown in FIG. 1, the opposite side view being identical thereto;

FIG. 3 is a top plan view of the sash lock housing shown in FIG. 1; and,

FIG. 4 is a front elevation view of the sash lock housing shown in FIG. 1.

The bottom view and rear elevation view are plain and unornamented.

Features shown in broken lines in the drawings are not part of the claim.
